(57) **CLAIM**

I claim the ornamental design for a golf club head, as shown and described.

DESCRIPTION

FIG. 1 is a perspective view of a golf club head, as viewed from the front, top and one side.

FIG. 2 is a front elevation view of the golf club head of FIG. 1.

FIG. 3 is a rear elevation view of the golf club head of FIG. 1.

FIG. 4 is a side elevation view of a toe side of the golf club head of FIG. 1.

FIG. 5 is a side elevation view of a heel side of the golf club head of FIG. 1.

FIG. 6 is a top plan view of the golf club head of FIG. 1; and, FIG. 7 is a bottom plan view of the golf club head of FIG. 1.

The broken lines in the drawings are for purposes of illustrating environmental structure as well as portions of the design that form no part of the present claimed design. Portions of a face of the golf club head are stippled differently to illustrate that interior areas of honeycomb design features have a color which contrasts with the color of interstice areas between the honeycomb features.

1 Claim, 6 Drawing Sheets
